UNITED STATES PATENT OFFICE

146,578

DESIGN FOR A GAME DEVICE OR SIMILAR ARTICLE

Ted Kirik, New York, N. Y.

Application January 12, 1946, Serial No. 125,504

Term of patent 14 years

(Cl. D34—5)

To all whom it may concern:

Be it known that I, Ted Kirik, a citizen of the United States of America, residing at Bronx, New York, county of Bronx, and State of New York, have invented a new, original, and ornamental Design for a Game Device or Similar Article, of which the following is a specification, reference being had to the accompanying drawing, forming a part thereof.

Fig. 1 is a top plan view of a game device showing my new design;

Fig. 2 is an elevational view thereof;

Fig. 3 is a bottom plan view of the base portion of the game device shown in Fig. 1.

I claim:

The ornamental design for a game device or similar article, as shown.

TED KIRIK.
